UNITED STATES PATENT OFFICE.

MARIO AMADUCCI, OF MARTINEZ, CALIFORNIA.

FOLDING TABLE OR SIMILAR ARTICLE.

Application filed June 11, 1927. Serial No. 198,270.

This invention relates to improvements in folding tables or similar articles of the type adapted to be folded into compact forms.

An object of my invention is to provide 5 a folding table, bench or seat in which the legs can be folded against the top or can be firmly held in an open position.

A further object of my invention is to provide a folding table or similar article where- 10 in the legs may be maintained in a folded position against the top or may be maintained in an open condition.

Other objects more or less apparent will 15 present themselves or will be specifically pointed out in the description to follow.

In the accompanying drawings forming a part of this application:

Fig. 1 is a perspective view of a table or 20 similar article embodying my invention; Fig. 2 is a bottom plan view of the same with the legs unfolded and the table set up;

Fig. 3 is a bottom plan view of the same 25 with the legs folded against the top;

Fig. 4 is a sectional view of a portion of a 30 leg showing the manner in which the metallic supporting bars are attached to the legs;

Fig. 5 is a sectional view taken on the line 35 5—5 of Fig. 2; and

Fig. 6 is a sectional view taken on the line 40 6—6 of Fig. 2.

Referring to the drawings, the letter A designates a top which may assume any suitable form and may be constructed in any suitable manner such as from a plurality 45 of parallel boards 1 secured adjacent their ends by screws or other suitable means to cross members 2. Extending through the boards 1 and positioned in planes parallel to the cross members 2, are two rods 3 and 4, the former having two supporting legs 5 pivotally attached thereon adjacent its ends and the latter having two supporting legs 6 similarly attached thereto.

The two legs 6 are maintained in a separated position from the two end boards 1 by spacing collars 7, while the other two legs 5 are positioned in contact with the edges of the said two end boards but separated from the next adjacent two boards by similar spacing collars 8. Thus the two legs 5 which are positioned adjacent the collars 8 are farther apart than are the two legs 6 positioned adjacent collars 7.

Cross braces 9 are attached by screws to the 55 edges of the legs 6 and similar cross braces 10 are attached to the edges of the legs 5,

the said braces being adapted to maintain the ends of the legs in suitable supporting positions.

Suitably secured to and extending trans- 60 versely across the middle parts of those boards 1 which are positioned between the two end boards, is a brace member 11 having a pivoted clamping member 12 attached to its central part.

A U-shaped support 13 having its ends 65 movably extending through the legs 5, is adapted to extend across and rest against the underneath surface of boards 1 and against an edge of the brace member 11, thereby 70 maintaining the said legs 5 in a proper unfolded and supporting position.

Another U-shaped support 14 having its 75 ends movably extending through the legs 6, is adapted to extend across and rest against the underneath surface of some of the boards 1 and against the opposite edge of the brace member 11, thereby maintaining the said legs 6 in a proper unfolded and supporting position.

When it is desired to collapse the device or 80 fold the legs, the U-shaped supports 13 and 14 are pulled downwardly until they are separated from the brace member 11, after which the legs 5 and 6 are moved inwardly until they 85 are positioned parallel to and adjacent the two end boards 1. The U-shaped supports 13 and 14 are thereafter positioned against the top A, and the clamping member 12 is turned until its ends extend over the cross braces 9 90 and 10, thereby maintaining the legs, cross braces and U-shaped supports against the top A. A handle 15, secured to the outer edge of 95 one of the end boards 1, serves as a means for conveniently carrying the device.

It is apparent to those skilled in the art that the various parts of my improved table or similar article may be constructed from any suitable materials and may assume shapes other than those herein shown. It is therefore desired that my invention be included broadly within the spirit of the appended claims, and not restricted to the exact construction shown and described.

Having described my invention, what I 105 claim is:

1. A device of the class described comprising in combination with a top having two pair of legs pivotally attached thereto, of a cross brace secured to each pair of legs, a 110 brace member secured to the underneath side of the top, a pair of U-shaped supports each

pivottally attached at its ends to a pair of the legs and each support being adapted to removably rest against the brace member to maintain the legs in an upright position, and
5 clamping means movably attached to the brace member and adapted to extend over the cross braces, whereby the legs may be held against the top.

2. A device of the class described comprising in combination with a top having two pair of legs pivotally attached thereto, of a brace member secured to the underneath side of the top, a plurality of cross members secured to

the legs, a pair of U-shaped supports each pivotally attached at its ends to a pair of the legs and each support being adapted to removably rest against the brace member to maintain the legs in an upright position, and means for maintaining the legs in a folded position adjacent the top when the U-shaped supports are disengaged from the brace member, which said means comprises a clamping member pivotally attached to the brace member and adapted to extend over the cross members.

MARIO AMADUCCI.
